Co-Pending Application, Benjamin Phelan Oates, U.S. Appl. No. 29/596,260, filed Mar. 7, 2017.

(Continued)

Primary Examiner — Dana L Meyrow*(74) Attorney, Agent, or Firm* — Karen E. Klumas(57) **CLAIM**

The ornamental design for a bottle, as shown and described.

DESCRIPTION

FIG. 1 is a top, front and side perspective view of a bottle in accordance with my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The evenly-dashed broken lines in the drawings illustrate the portions of the bottle that form no part of the claim. The dot-dash broken lines in the drawings define the bounds of the claim and form no part thereof.

1 Claim, 5 Drawing Sheets(56)
